UNITED STATES PATENT OFFICE.

FLORENCE N. LEWIS, OF NEW YORK, N. Y.

DESIGN FOR A PERFUME BOTTLE.

Application filed August 18, 1927. Serial No. 23,144. Term of patent 14 years.

To all whom it may concern:

Be it known that I, FLORENCE N. LEWIS, a citizen of the United States, residing at New York, in the county of New York, State of New York, have invented a new, original, and ornamental perfume bottle, of which the following is a specification, reference being had to the accompanying drawing, forming a part thereof.

I claim:

The ornamental design for a perfume bottle, as shown.

FLORENCE N. LEWIS.
